UNITED STATES PATENT OFFICE.

MORTON L. MUNSON, OF LANSING, MICHIGAN.

FISH SCALER.

Application filed June 23, 1924. Serial No. 722,951.

To all whom it may concern:

Be it known that I, MORTON L. MUNSON, a citizen of the United States, residing at Lansing, county of Ingham, State of Michigan, have invented certain new and useful Improvements in Fish Scalers, of which the following is a specification.

This invention relates to improvements in fish scalers.

10 The main object of this invention is to provide an improved fish scaler which is very economical to produce and at the same time is efficient, strong and durable.

15 Objects pertaining to details and economies of my invention will definitely appear from the detailed description to follow.

20 I accomplish the objects of my invention by the devices and means described in the following specification. The invention is clearly defined and pointed out in the claims.

25 A structure which is a preferred embodiment of my invention is clearly illustrated in the accompanying drawing forming a part of this application, in which:

Fig. I is a perspective view of my improved fish scaler.

Fig. II is a sectional view on a line corresponding to line 2—2 in Fig. I.

30 In the drawing similar numerals of reference indicate similar parts in both views.

Referring to the drawing, my improved implement comprises a handle 1 having a cylindrical portion 2 with a longitudinal groove 3 therein. The blade 4 is formed as a sheet metal stamping and has an integral shank portion 5 disposed substantially at right angles to the blade and terminating in a coil 6.

35 This coil 6 is of such diameter as to embrace the portion 2 of the handle under spring tension, the coil terminating in an inturned flange 7 engaged in the groove 3, the spring action holding this flange in the

groove. The coil is turned rearwardly relative to the shank so that any pressure exerted 45 on the blade tends to clamp the shank to the handle rather than to loosen or disengage the same. The edge of the blade is preferably serrated as illustrated.

The parts of my improved implement are 50 very economical to produce, are easily assembled and at the same time the structure is very strong and durable, any shrinking of the wood handle being compensated for by the spring engagement of the shank there- 55 with.

Further, as it is not necessary to bore the handle, as is necessary when the blades are provided with tangs, the handle is not weakened or likely to be split so it is not necessary to use high grade wood. 60

Having thus described my invention what I claim as new and desire to secure by Letters Patent is:

1. An implement of the class described 65 comprising a handle having a cylindrical portion with a longitudinal groove therein, and a serrated blade having an integral shank disposed at an angle thereto and terminating in a coil embracing said cylindrical portion of said handle under spring tension 70 and having an inturned flange at its longitudinal edge engaged in said groove in said handle.

2. An implement of the class described 75 comprising a handle having a cylindrical portion with a longitudinal groove therein, and a blade having a shank portion terminating in a coil embracing said cylindrical portion of said handle under spring tension 80 and having an inturned flange at its longitudinal edge engaged in said groove in said handle.

In witness whereof I have hereunto set my hand.

MORTON L. MUNSON. [L. s.]
